UNITED STATES PATENT OFFICE

165,725

DOLL OR SIMILAR ARTICLE

Jacob Swedlin, Rockville Centre, N. Y.

Application December 27, 1949, Serial No. 6,846

Term of patent 7 years

(Cl. D34—4)

To all whom it may concern:

Be it known that I, Jacob Swedlin, a citizen of the United States, residing at Rockville Centre, in the county of Nassau and State of New York, have invented a new, original, and ornamental Design for Doll or Similar Article, of which the following is a specification; reference being had to the accompanying drawing, forming a part thereof.

Fig. 1 is a front perspective view of a doll or similar article, showing my new design.

Fig. 2 is a rear perspective view thereof.

Fig. 3 is a side view thereof.

I claim:

The ornamental design for a doll or similar article, substantially as shown.

JACOB SWEDLIN.
